(57) **CLAIM**

The ornamental design for stemware, as shown and described.

DESCRIPTION

FIG. 1 shows a perspective view of stemware made in accordance with the design of the present invention;

FIG. 2 shows a right side view of the stemware of FIG. 1;

FIG. 3 shows a left side view of the stemware of FIG. 1;

FIG. 4 shows an end view of the stemware of FIG. 1;

FIG. 5 shows an opposing end view of the stemware of FIG. 1;

FIG. 6 shows a bottom view of the stemware of FIG. 1;

FIG. 7 shows a top view of the stemware of FIG. 1; and,

FIG. 8 shows an alternative top plan view of the stemware with the cup portion removed for clarity.

The broken lines in the drawings represent portions of the structure that form no part of the claim.
